Primary Examiner — David S Warren*(74) Attorney, Agent, or Firm* — Xsensus LLP(57) **ABSTRACT**

In an elevator operation panel, a base of a casing includes a back plate portion, a lateral plate portion, and a vertical plate portion. An outer surface of the lateral plate portion, which faces the exterior of the casing, and a vertical direction end surface of the vertical plate portion on the lateral plate portion side are disposed in an identical plane. An L-shaped slit is provided between the back plate portion and the lateral plate portion. The slit includes a rectilinear portion, and a projecting portion that projects into the back plate portion. In a condition where the lateral plate portion is bent relative to the back plate portion, a surface of the lateral plate portion that faces the rectilinear portion overlaps a surface of the back plate portion on an opposite side to a wall.

ELEVATOR OPERATION PANEL

TECHNICAL FIELD

This invention relates to an elevator operation panel, such as a car operation panel provided inside a cage or a landing operation panel provided on a landing, for example.

BACKGROUND ART

In a type of elevator, among conventional elevators, in which a casing of a car operation panel is embedded in a cage wall (a wing wall or a side face wall), the front surface is the only part of the car operation panel that is exposed to the cage interior.

In a type of elevator in which the car operation panel is fixed to the surface of the cage wall, however, the casing of the car operation panel is exposed to the cage interior, which is undesirable in terms of design. Moreover, when the cage wall deforms unexpectedly, an angled portion of the casing may protrude from the cage wall and become caught on clothing, luggage, or the like. Furthermore, when the angled portion of the casing is sharp, great care must be taken not to damage the cage wall and so on during installation, which is undesirable in terms of workability.

In a conventional control panel casing proposed in response to these problems, a slit is provided between a side plate portion and an upper plate portion of a partition plate (see PTL 1, for example).

CITATION LIST

Patent Literature

[PTL 1] Japanese Patent Application Publication No. 2001-217574

SUMMARY OF THE INVENTION

Problem to be Solved by the Invention

However, even with the conventional control panel casing described above, when the control panel casing is applied to a type of elevator in which the car operation panel is fixed to the surface of the cage wall, the sharp angled portions are exposed to the cage interior, and therefore, when the cage wall deforms unexpectedly, the angled portions may become caught on clothing or luggage. Moreover, the workability decreases during installation.

This invention has been designed to solve the problems described above, and an object thereof is to obtain an elevator operation panel with which the exposure of sharp angled portions can be reduced.

Means for Solving the Problem

An elevator operation panel according to this invention includes a casing having a base and a cover joined to the base, wherein: the base includes a back plate portion fixed to a wall, a lateral plate portion projecting at a right angle toward the cover side from a vertical direction end portion of the back plate portion, and a vertical plate portion projecting at a right angle toward the cover side from a width direction end portion of the back plate portion; the back plate portion, the lateral plate portion, and the vertical plate portion are formed by bending a single flat plate; an outer surface of the lateral plate portion, which faces the exterior

2

of the casing, and a vertical direction end surface of the vertical plate portion on the lateral plate portion side are disposed in an identical plane; an L-shaped slit is provided between the back plate portion and the lateral plate portion; the slit includes a rectilinear portion provided to extend in a width direction of the lateral plate portion from a width direction end portion of the lateral plate portion on the vertical plate portion side, and a projecting portion that projects into the back plate portion from an end portion of the rectilinear portion on an opposite side to the vertical plate portion; and in a condition where the lateral plate portion is bent relative to the back plate portion, a surface of the lateral plate portion that faces the rectilinear portion overlaps a surface of the back plate portion on an opposite side to the wall.

Further, an elevator operation panel according to this invention includes a casing having a base and a cover joined to the base, wherein: the base includes a back plate portion fixed to a wall, a lateral plate portion projecting at a right angle toward the cover side from a vertical direction end portion of the back plate portion, and a vertical plate portion projecting at a right angle toward the cover side from a width direction end portion of the back plate portion; the back plate portion, the lateral plate portion, and the vertical plate portion are formed by bending a single flat plate; an outer surface of the vertical plate portion, which faces the exterior of the casing, and a width direction end surface of the lateral plate portion on the vertical plate portion side are disposed in an identical plane; an L-shaped slit is provided between the back plate portion and the vertical plate portion; the slit includes a rectilinear portion provided to extend in a vertical direction from a vertical direction end portion of the vertical plate portion on the lateral plate portion side, and a projecting portion that projects into the back plate portion from an end portion of the rectilinear portion on an opposite side to the lateral plate portion; and in a condition where the vertical plate portion is bent relative to the back plate portion, a surface of the vertical plate portion that faces the rectilinear portion overlaps a surface of the back plate portion on an opposite side to the wall.

Effects of the Invention

With the elevator operation panel according to this invention, by providing the L-shaped slit, a hole formed during bending can be shifted to the back plate portion, and as a result, the exposure of sharp angled portions can be reduced.

BRIEF DESCRIPTION OF THE DRAWINGS

FIG. 1 is a front view showing an arrangement of a car operation panel for an elevator according to a first embodiment of this invention.

FIG. 2 is an enlarged front view showing the car operation panel of FIG. 1.

FIG. 3 is a right side view showing the car operation panel of FIG. 2.

FIG. 4 is a bottom view showing the car operation panel of FIG. 2.

FIG. 5 is a front view showing a base of FIG. 3.

FIG. 6 is a development diagram showing the base of FIG. 5.

FIG. 7 is an enlarged front view showing a VII part of FIG. 6.

FIG. 8 is an enlarged front view showing a VIII part of FIG. 5.

FIG. 9 is a back view of a part shown in FIG. 8.

FIG. 10 is a front view showing a base of a casing of a car operation panel according to a second embodiment of this invention.

FIG. 11 is a development diagram showing the base of FIG. 10.

DESCRIPTION OF EMBODIMENTS

Embodiments of this invention will be described below with reference to the drawings.

First Embodiment

FIG. 1 is a front view showing an arrangement of a car operation panel for an elevator according to a first embodiment of this invention. In the drawing, a pair of car doors *2a*, *2b* for opening and closing a car doorway *1* are provided on a front surface of a cage. A pair of wing walls *3a*, *3b* are provided on respective sides of the car doorway *1*. A car operation panel *4* is fixed to the wing wall *3a*.

FIG. 2 is an enlarged front view showing the car operation panel *4* of FIG. 1. FIG. 3 is a right side view showing the car operation panel *4* of FIG. 2. FIG. 4 is a bottom view showing the car operation panel *4* of FIG. 2. The car operation panel *4* includes a casing *5* and a plurality of operation panel devices incorporated into the casing *5*.

The operation panel devices include an indicator *6*, a car operating button device *7*, a control box (not shown), and so on. An LED indicator, for example, is used as the indicator *6*. A plurality of destination floor specifying buttons that are operated from inside the cage are provided in the car operating button device *7*.

The casing *5* has a thin, vertically long outer shape in which a height dimension (a dimension in a vertical direction of FIG. 2) is larger than a width dimension (a dimension in a left-right direction of FIG. 2) and a thickness dimension (a dimension in a left-right direction of FIG. 3) is smaller than the width dimension.

Further, the casing *5* includes a base (a box) *11* fixed to the wing wall *3a*, and a cover (a face plate) *12* joined to the base *11*. The cover *12* is fixed to the base *11* by two screws *13* in a lower portion of the casing *5*.

The base *11* includes a back plate portion *111* that overlaps and is fixed to a surface of the wing wall *3a*, a base upper plate portion *112* that projects at a right angle toward the cover *12* side (an opposite side to the wing wall *3a*) from an upper end portion of the back plate portion *111*, a base lower plate portion *113* that projects at a right angle toward the cover *12* side from a lower end portion of the back plate portion *111*, and first and second base side plate portions *114*, *115* that project at right angles toward the cover *12* side from respective width direction end portions of the back plate portion *111*.

The back plate portion *111*, the base upper plate portion *112*, the base lower plate portion *113*, the first base side plate portion *114*, and the second base side plate portion *115* are formed by bending a single flat steel plate. The back plate portion *111* has a rectangular surface shape.

The cover *12* includes a front surface portion *121* that opposes the back plate portion *111*, a cover upper plate portion *122* that projects at a right angle toward the base *11* side (the wing wall *3a* side) from an upper end portion of the front surface portion *121*, a cover lower plate portion *123* that projects at a right angle toward the base *11* side from a lower end portion of the front surface portion *121*, and first and second cover side plate portions *124*, *125* that project at

right angles toward the base *11* side from respective width direction end portions of the front surface portion *121*.

The cover upper plate portion *122* partially overlaps the base upper plate portion *112*. The first cover side plate portion *124* partially overlaps an outer side of the first base side plate portion *114*. The second cover side plate portion *125* partially overlaps an outer side of the second base side plate portion *115*.

A base *11* side end surface of the cover lower plate portion *123* opposes a cover *12* side end surface of the base lower plate portion *113*. A pair of tool insertion holes *123a* for inserting a tool for rotating the screws *13*, for example a screwdriver, are provided in the cover lower plate portion *123* serving as a lower end portion of the casing *5*.

FIG. 5 is a front view showing the base *11* of FIG. 3. The base upper plate portion *112* includes an upper plate portion upper surface *112a*, serving as an outer surface that faces the exterior of the casing *5*, an upper plate portion lower surface *112b* serving as an inner surface that faces the interior of the casing *5*, a width direction first end surface *112c*, and a width direction second end surface *112d*.

The base lower plate portion *113* includes a lower plate portion lower surface *113a* serving as an outer surface that faces the exterior of the casing *5*, a lower plate portion upper surface *113b* serving as an inner surface that faces the interior of the casing *5*, a width direction first end surface *113c*, and a width direction second end surface *113d*.

The lower plate portion upper surface *113b* faces the upper plate portion lower surface *112b*. The upper plate portion upper surface *112a* is a surface of the base upper plate portion *112* on an opposite side to a surface (the upper plate portion lower surface *112b*) thereof that opposes the base lower plate portion *113*. The lower plate portion lower surface *113a* is a surface of the base lower plate portion *113* on an opposite side to a surface (the lower plate portion upper surface *113b*) thereof that opposes the base upper plate portion *112*.

The first base side plate portion *114* includes a first side plate portion outer surface *114a* serving as an outer surface that faces the exterior of the casing *5*, a first side plate portion inner surface *114b* serving as an inner surface that faces the interior of the casing *5*, a first upper end surface *114c* serving as a vertical direction end surface on the base upper plate portion *112* side, and a first lower end surface *114d* serving as a vertical direction end surface on the base lower plate portion *113* side.

The second base side plate portion *115* includes a second side plate portion outer surface *115a* serving as an outer surface that faces the exterior of the casing *5*, a second side plate portion inner surface *115b* serving as an inner surface that faces the interior of the casing *5*, a second upper end surface *115c* serving as a vertical direction end surface on the base upper plate portion *112* side, and a second lower end surface *115d* serving as a vertical direction end surface on the base lower plate portion *113* side.

The second side plate portion inner surface *115b* opposes the first side plate portion inner surface *114b*. The first side plate portion outer surface *114a* is a surface of the first base side plate portion *114* on an opposite side to a surface (the first side plate portion inner surface *114b*) thereof that opposes the second base side plate portion *115*. The second side plate portion outer surface *115a* is a surface of the second base side plate portion *115* on an opposite side to a surface (the second side plate portion inner surface *115b*) thereof that opposes the first base side plate portion *114*.

The base upper plate portion *112* is disposed between respective upper end portions of the first and second base

side plate portions 114, 115. The upper plate portion upper surface 112a, the first upper end surface 114c, and the second upper end surface 115c are disposed in an identical horizontal plane. The first end surface 112c of the base upper plate portion 112 either contacts or opposes via a very small gap the upper end portion of the first side plate portion inner surface 114b. The second end surface 112d of the base upper plate portion 112 either contacts or opposes via a very small gap the upper end portion of the second side plate portion inner surface 115b.

The base lower plate portion 113 is disposed between respective lower end portions of the first and second base side plate portions 114, 115. The lower plate portion lower surface 113a, the first lower end surface 114d, and the second lower end surface 115d are disposed in an identical horizontal plane. The first end surface 113c of the base lower plate portion 113 either contacts or opposes via a very small gap the lower end portion of the first side plate portion inner surface 114b. The second end surface 113d of the base lower plate portion 113 either contacts or opposes via a very small gap the lower end portion of the second side plate portion inner surface 115b.

The base upper plate portion 112 and the base lower plate portion 113 constitute a lateral plate portion according to the first embodiment. The first base side plate portion 114 and the second base side plate portion 115 constitute a vertical plate portion according to the first embodiment.

FIG. 6 is a development diagram showing the base 11 of FIG. 5. FIG. 7 is an enlarged front view showing a VII part of FIG. 6. FIG. 8 is an enlarged front view showing a VIII part of FIG. 5. FIG. 9 is a back view of a part shown in FIG. 8. L-shaped first and second slits 21, 22 are provided between the back plate portion 111 and the base upper plate portion 112. Further, L-shaped third and fourth slits 23, 24 are provided between the back plate portion 111 and the base lower plate portion 113.

The first and second slits 21, 22 are disposed in left-right symmetry about the width direction (a left-right direction of FIG. 6) of the base 11. Similarly, the third and fourth slits 23, 24 are disposed in left-right symmetry about the width direction of the base 11.

The first slit 21 includes a first rectilinear portion 21a provided to extend in the width direction of the base upper plate portion 112 from a width direction end portion (a left-right direction end portion in FIG. 6) of the base upper plate portion 112 on the first base side plate portion 114 side, and a first projecting portion 21b that projects into the back plate portion 111 from an end portion of the first rectilinear portion 21a on an opposite side to the first base side plate portion 114.

The second slit 22 includes a second rectilinear portion 22a provided to extend in the width direction of the base upper plate portion 112 from a width direction end portion of the base upper plate portion 112 on the second base side plate portion 115 side, and a second projecting portion 22b that projects into the back plate portion 111 from an end portion of the second rectilinear portion 22a on an opposite side to the second base side plate portion 115.

The third slit 23 includes a third rectilinear portion 23a provided to extend in the width direction of the base lower plate portion 113 from a width direction end portion (a left-right direction end portion in FIG. 6) of the base lower plate portion 113 on the first base side plate portion 114 side, and a third projecting portion 23b that projects into the back plate portion 111 from an end portion of the third rectilinear portion 23a on an opposite side to the first base side plate portion 114.

The fourth slit 24 includes a fourth rectilinear portion 24a provided to extend in the width direction of the base lower plate portion 113 from a width direction end portion of the base lower plate portion 113 on the second base side plate portion 115 side, and a fourth projecting portion 24b that projects into the back plate portion 111 from an end portion of the fourth rectilinear portion 24a on an opposite side to the second base side plate portion 115.

In a condition where the base upper plate portion 112 and the base lower plate portion 113 are bent relative to the back plate portion 111, a surface of the base upper plate portion 112 that faces the first and second rectilinear portions 21a, 22a and a surface of the base lower plate portion 113 that faces the third and fourth rectilinear portions 23a, 24a overlap a surface of the back plate portion 111 on the opposite side to the wing wall 3a. In other words, wall surfaces of the rectilinear portions 21a, 22a on the base upper plate portion 112 side and wall surfaces of the rectilinear portions 23a, 24a on the base lower plate portion 113 side either contact the back plate portion 111 or oppose the back plate portion 111 via a very small gap.

A length L1 (FIG. 7) from an open end of the rectilinear portion 21a, 22a, 23a, 24a to the projecting portion 21b, 22b, 23b, 24b is preferably at least three times the plate thickness.

As shown in FIG. 7, by providing the slits 23, 24 with the respective projecting portions 23b, 24b, a center line C2 of a bent portion of the base lower plate portion 113 that is bent relative to the back plate portion 111 deviates upward from the first and second lower end surfaces 114d, 115d by W1. In vertical symmetry therewith, a center line C1 of a bent portion of the base upper plate portion 112 that is bent relative to the back plate portion 111 deviates downward from the first and second upper end surfaces 114c, 115c by W1.

Further, the first end surfaces 112c, 113c and the second end surfaces 112d, 113d deviate inwardly in the width direction of the base 11 by W2 from center lines C3, C4 of respective bent portions of the first and second base side plate portions 114, 115 that are bent relative to the back plate portion 111.

Hence, in the operation panel 4 for an elevator according to the first embodiment, the first and second slits 21, 22 are provided between the back plate portion 111 and the base upper plate portion 112, and the third and fourth slits 23, 24 are provided between the back plate portion 111 and the base lower plate portion 113. Further, the upper plate portion upper surface 112a, the first upper end surface 114c, and the second upper end surface 115c are disposed in an identical horizontal plane. Moreover, the lower plate portion lower surface 113a, the first lower end surface 114d, and the second lower end surface 115d are disposed in an identical horizontal plane. As a result, the exposure of angled portions in the four corners of the base 11 can be reduced.

Furthermore, the first to fourth slits 21, 22, 23, 24 are formed in an L shape, and therefore holes formed when the base upper plate portion 112 and the base lower plate portion 113 are bent, or in other words the projecting portions 21b, 22b, 23b, 24b, can be shifted to the back plate portion 111. As a result, the exposure of sharp angled portions can be reduced.

Moreover, the base 11 can be manufactured from a single steel plate, and therefore superior material efficiency is obtained.

Furthermore, neither welding nor corner chamfering implemented as post-processing is required, and therefore the amount of required processing can be reduced.

Further, the slits 21, 22, 23, 24 are provided between the back plate portion 111 and the base upper plate portion 112 and base lower plate portion 113, and therefore the slits 21, 22, 23, 24 can be made less obvious. As a result, deterioration of the design property can be prevented.

Second Embodiment

Next, FIG. 10 is a front view showing a base of a casing of a car operation panel according to a second embodiment of this invention, and FIG. 11 is a development diagram showing the base of FIG. 10.

The first base side plate portion 114 is disposed between a width direction first end portion of the base upper plate portion 112 and a width direction first end portion of the base lower plate portion 113. The first side plate portion outer surface 114a and the first end surfaces 112c, 113c are disposed in an identical vertical plane. The first upper end surface 114c either contacts or opposes via a very small gap the width direction first end portion of the upper plate portion lower surface 112b. The first lower end surface 114d either contacts or opposes via a very small gap the width direction first end portion of the lower plate portion upper surface 113b.

The second base side plate portion 115 is disposed between a width direction second end portion of the base upper plate portion 112 and a width direction second end portion of the base lower plate portion 113. The second side plate portion outer surface 115a and the second end surfaces 112d, 113d are disposed in an identical vertical plane. The second upper end surface 115c either contacts or opposes via a very small gap the width direction second end portion of the upper plate portion lower surface 112b. The second lower end surface 115d either contacts or opposes via a very small gap the width direction second end portion of the lower plate portion upper surface 113b.

The base upper plate portion 112 and the base lower plate portion 113 constitute a lateral plate portion according to the second embodiment. The first base side plate portion 114 and the second base side plate portion 115 constitute a vertical plate portion according to the second embodiment.

L-shaped first and second slits 31, 32 are provided between the back plate portion 111 and the first base side plate portion 114. Further, L-shaped third and fourth slits 33, 34 are provided between the back plate portion 111 and the second base side plate portion 115.

The first and second slits 31, 32 are disposed in vertical symmetry about the vertical direction of the base 11. Similarly, the third and fourth slits 33, 34 are disposed in vertical symmetry about the vertical direction of the base 11.

The first slit 31 includes a first rectilinear portion 31a provided to extend in a vertical direction from an upper end portion of the first base side plate portion 114, and a first projecting portion 31b that projects into the back plate portion 111 from an end portion (a lower end portion) of the first rectilinear portion 31a on an opposite side to the base upper plate portion 112.

The second slit 32 includes a second rectilinear portion 32a provided to extend in a vertical direction from a lower end portion of the first base side plate portion 114, and a second projecting portion 32b that projects into the back plate portion 111 from an end portion (an upper end portion) of the second rectilinear portion 32a on an opposite side to the base lower plate portion 113.

The third slit 33 includes a third rectilinear portion 33a provided to extend in a vertical direction from an upper end portion of the second base side plate portion 115, and a third

projecting portion 33b that projects into the back plate portion 111 from an end portion (a lower end portion) of the third rectilinear portion 33a on an opposite side to the base upper plate portion 112.

5 The fourth slit 34 includes a fourth rectilinear portion 34a provided to extend in a vertical direction from a lower end portion of the second base side plate portion 115, and a fourth projecting portion 34b that projects into the back plate portion 111 from an end portion (an upper end portion) of the fourth rectilinear portion 34a on an opposite side to the base lower plate portion 113.

In a condition where the first and second base side plate portions 114, 115 are bent relative to the back plate portion 111, a surface of the first base side plate portion 114 that faces the first and second rectilinear portions 31a, 32a and a surface of the second base side plate portion 115 that faces the third and fourth rectilinear portions 33a, 34a overlap the surface of the back plate portion 111 on the opposite side to the wing wall 3a. In other words, wall surfaces of the rectilinear portions 31a, 32a on the first base side plate portion 114 side and wall surfaces of the rectilinear portions 33a, 34a on the second base side plate portion 115 side either contact the back plate portion 111 or oppose the back plate portion 111 via a very small gap.

By providing the slits 31, 32 with the respective projecting portions 31b, 32b, center lines C3, C4 of respective bent portions of the first and second base side plate portions 114, 115 that are bent relative to the back plate portion 111 deviate inwardly in the width direction of the base by W1 (FIG. 7) from the first end surfaces 112c, 113c and the second end surfaces 112d, 113d.

The first and second upper end surfaces 114c, 115c deviate downward by W2 (FIG. 7) from the center line C1 of the bent portion of the base upper plate portion 112 that is bent relative to the back plate portion 111. In vertical symmetry thereto, the first and second lower end surfaces 114d, 115d deviate upward by W2 from the center line C2 of the bent portion of the base lower plate portion 113 that is bent relative to the back plate portion 111. All other configurations are similar or identical to the first embodiment.

Likewise with this configuration, exposure of the angled portions in the four corners of the base 11 can be reduced. Further, the holes that are formed when the first and second base side plate portions 114, 115 are bent, or in other words the projecting portions 31b, 32b, 33b, 34b, can be shifted to the back plate portion 111, whereby exposure of the sharp angled portions can be reduced. Moreover, the base can be manufactured from a single steel plate, and therefore superior material efficiency is obtained. Furthermore, neither welding nor corner chamfering implemented as post-processing is required, and therefore the amount of required processing can be reduced.

50 Note that in the examples described above, the slits are disposed in the four corners of the base, but the slits do not necessarily have to be disposed in all four corners.

Further, this invention may also be applied to a landing operation panel for an elevator.

60 The invention claimed is:

1. An elevator operation panel, comprising a casing having a base and a cover joined to the base, wherein the base includes a back plate portion fixed to a wall, a lateral plate portion projecting at a right angle toward the cover side from a vertical direction end portion of the back plate portion, and a vertical plate

9

portion projecting at a right angle toward the cover side from a width direction end portion of the back plate portion, the back plate portion, the lateral plate portion, and the vertical plate portion are formed by bending a single flat plate, an outer surface of the lateral plate portion, which faces the exterior of the casing, and a vertical direction end surface of the vertical plate portion on the lateral plate portion side are disposed in an identical plane, 5 an L-shaped slit is provided between the back plate portion and the lateral plate portion, the slit includes a rectilinear portion provided to extend in a width direction of the lateral plate portion from a width direction end portion of the lateral plate portion on the vertical plate portion side, and a projecting portion that projects into the back plate portion from an end portion of the rectilinear portion on an opposite side to the vertical plate portion, and 10 in a condition where the lateral plate portion is bent relative to the back plate portion, a surface of the lateral plate portion that faces the rectilinear portion overlaps a surface of the back plate portion on an opposite side to the wall.

2. An elevator operation panel, comprising a casing 25 having a base and a cover joined to the base, wherein the base includes a back plate portion fixed to a wall, a lateral plate portion projecting at a right angle

10

toward the cover side from a vertical direction end portion of the back plate portion, and a vertical plate portion projecting at a right angle toward the cover side from a width direction end portion of the back plate portion, the back plate portion, the lateral plate portion, and the vertical plate portion are formed by bending a single flat plate, an outer surface of the vertical plate portion, which faces the exterior of the casing, and a width direction end surface of the lateral plate portion on the vertical plate portion side are disposed in an identical plane, an L-shaped slit is provided between the back plate portion and the vertical plate portion, the slit includes a rectilinear portion provided to extend in a vertical direction from a vertical direction end portion of the vertical plate portion on the lateral plate portion side, and a projecting portion that projects into the back plate portion from an end portion of the rectilinear portion on an opposite side to the lateral plate portion, and 10 in a condition where the vertical plate portion is bent relative to the back plate portion, a surface of the vertical plate portion that faces the rectilinear portion overlaps a surface of the back plate portion on an opposite side to the wall.
